PLUG FUSE

Martin Henry White, Yonkers, N. Y.

Application November 7, 1934, Serial No. 751,798

5 Claims. (Cl. 200—121)

This invention relates to new and useful improvements in a plug fuse.

The invention has for an object the construction of a plug fuse which is characterized by a body consisting of a head section of transparent material and a foot section, and including a fuse element arranged within a compartment in the head section so as to be viewable through the head end thereof.

10 More particularly, the invention contemplates arranging the head section with a bulged portion acting as a magnifying glass so that the fuse element may be seen with greater ease.

Another object of the invention is to arrange 15 the head section and the foot section to prevent twisting of the connecting wires.

Another one of the objects of this invention is the arrangement of a neon glow lamp in the compartment of the head section and beneath 20 the fuse element, and arranged in a circuit and associated with a circuit of the fuse element in such a manner that when the fuse blows the neon lamp will light and call attention to the fact. Further, because of the location of the 25 lamp and fuse element, when the lamp is illuminated, the fuse element may readily be seen ruptured.

Still further, the invention also contemplates 30 an arrangement wherein the foot section of the body is composed of a stationary part and a movable part, and mechanism associated with the movable part in such a manner that the fuse element may be taken out of the circuit to permit testing of the lamp.

35 Another object of this invention is the construction of a device as mentioned which is simple and durable, and which can be manufactured and sold at a reasonable cost.

40 For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

50 Fig. 1 is a vertical sectional view of a plug fuse constructed according to this invention.

Fig. 2 is a horizontal sectional view taken on the line 2—2 of Fig. 1.

55 Fig. 3 is another horizontal sectional view but taken on the line 3—3 of Fig. 1.

Fig. 4 is another horizontal sectional view, taken on the line 4—4 of Fig. 1.

Fig. 5 is a perspective view, showing some of the parts used in this invention.

Fig. 6 is a fragmentary sectional view similar 5 to a portion of Fig. 1 but illustrating a modified construction.

Fig. 7 is a horizontal sectional view taken on the line 7—7 of Fig. 6.

The plug fuse, according to this invention, includes a body comprising a head section 10 of transparent material, and a foot section 11. A threaded contact shell 12 of standard design is mounted upon the body and serves to hold the sections together in a unit. More particularly, 15 a portion of the head section is formed with threads engaged by the threads of the shell, and the outer end of the shell is formed with an inturned flange engaging over an edge portion of the foot section. An end contact 13 is 20 mounted upon the foot end of the body and a flange or bead 13' is formed at its upper face.

A recess in flange 13' is being engaged by a lug 11' of the foot portion 11 to prevent the end contact from rotation.

25 A fuse element 14 is arranged within the compartment 15 in said body, and is viewable through the head of the body. A neon glow lamp 16 is also disposed in the compartment 15 and arranged beneath the fuse element 14. A 30 resistance 17 of the "grid leak" type is disposed within the body as hereinafter further described.

The head section 10, preferably is made from glass material and at the top end is formed with a bulged portion 10^a acting as a magnifying glass 35 so that the fuse element 14 may be seen with greater detail. The compartment 15 extends into a location immediately below the magnifying portion 10^a. The fuse element 14 is arranged with a reduced fusible portion 14^a immediately beneath the magnifying portion 10^a. The body 10 is also formed with a top flange 10^b by which the fuse may be readily gripped when screwed into a standard socket.

The foot portion 11 is formed with a small projection 18 engaging into receiving opening in the head section so as to hold the parts against possible rotation and thus to prevent twisting of the connecting wires. The foot portion 11 is also provided with a cylindrical portion 11^a which extends into the compartment 15. This cylindrical portion may be filled with cement 19 into which the bottom of the lamp 16 is engaged so that the lamp is firmly fixed in position. The lamp 16 is also held firmly by the wire connections and the 55

locking arrangement of the invention. The lamp 16 includes a pair of spaced electrodes 20 which are firmly held in position with a supporting bead 21 of glass within the bulb of the lamp which is supported by wires 20' and 20^a.

The electrodes 20 are so located as to produce the maximum amount of signalling visibility which is accentuated by the bulged portion 10^a of head section 10 and thus magnifying the rays of light when the neon glow lamp is in operation. Wires 20' and 20^a extend from each of the electrodes out from the bottom end of the lamp.

The cylindrical portion 11^a may also be left without cement filling, if desired.

There is an electric circuit from the end contact 13 to the shell contact 12, and this circuit includes the resistance 17, the lamp 16, and a wire 20' electrically connected with the shell 12. There is another circuit also extending from the end contact 13 to the shell contact 12 and includes a fusible element 14 commencing at 14^b, passing through an opening 11^b in the side of the cylindrical portion 11^a and extending up between the outer wall of the cylindrical portion and the wall of the compartment 15. The circuit continues downward between the face of the compartment 15 and the outer face of the cylindrical portion 11^a and ends at 14^c.

The cylindrical portion 11 is formed with an opening 11^c through which the lead 20' from the terminal of the lamp extends with the extremity 14^c of fuse member 14, and both continue through an opening 10^c in head section 10 into a longitudinal slot 10^d. The wire 20' and fuse extremity 14^c are soldered at 12' to the shell contact 12.

In Figs. 6 and 7 a modified form of the invention has been disclosed wherein provision is made for the testing of the lamp when desired. More particularly, the device has a foot section 11' consisting of a stationary part 11^d, and a movable part 11^e. A control contact 23^a is connected with the end contact 13 by wire 14^d and mounted upon the movable part 11 and is adapted to engage a control contact 23^b mounted upon a stationary portion of the body in a certain position of the movable part. A pin 18' projects from the part 11^d into opening 18^a in a stationary part of the body so as to prevent motion of part 11^d. A set screw 25 engages through the stationary part 11^d and into the movable part 11^e to hold these parts fixed together against disengaging movement. The set screw 25 may be partially removed from the moveable part 11^e so as to engage a peripheral groove 11^f and to permit the movement of the last said part from the contacting position described, to a position in which contacts 23^a and 23^b are disengaged. The control contacts 23^a and 23^b are arranged in series in the fuse element circuit.

The operation of the device is as follows: The fuse element 14 may easily be examined when the plug fuse is out of a conventional socket, because of the enlarging qualities of the magnifying glass portion. When the plug fuse is used, it is engaged into a receiving socket in conventional fashion. The glow lamp will not be illuminated because of internal resistance and resistance 17, the current passing through the circuit which includes the fuse element 14. In the event that the load through the fuse element is too great, it will burn and fuse and so break one of the circuits for the current. The current will therefore take the circuit through the glow lamp which will then be-

come illuminated. It is then an easy matter to detect that the fuse has blown.

Respecting the modified form shown in Figs. 6 and 7, with the contacts 23^a and 23^b engaged, the operation of the device is identical to that previously described. A feature of the construction is that the glow lamp may be tested by turning the movable part 11^e so as to break the circuit through the fuse element at the contacts 23^a and 23^b. When the plug fuse is then engaged in the socket, the lamp will glow if it is in proper operating condition. After the test, the movable part 11^e should be returned to close the circuit at the contacts 23^a and 23^b.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a plug fuse, a body consisting of a head section of transparent material and a foot section, a fuse element within a compartment in said body and viewable through the head end of the body, a neon glow lamp in said compartment and beneath said fuse element, an electric circuit for connection from an end contact of said body to a shell contact of said body and including a resistance and said lamp in series, another electric circuit from the end contact to the shell contact and including said fuse element in series, a cylindrical portion from the foot section engaging into the said compartment, and cement within the cylindrical portion for holding the lamp in a fixed position, said cylindrical portion having an outside diameter of smaller size than the compartment to produce a space between these parts, and said circuits, including wires passing through said space.

2. A plug fuse, comprising a body consisting of a head section of transparent material and a movable foot section, a threaded contact shell mounted on said body, an end contact on the foot end of said body, a fuse element within a compartment in said body and viewable through the head end of the body, a neon glow lamp in said compartment and beneath said fuse element, a resistance in said body, a control contact on the movable section and engageable with a control contact on the stationary portion of the body in a certain position of said movable section, an electric circuit from the end contact to the shell contact and including said resistant and lamp in series, and another electric circuit from the end contact to the shell contact and including the fuse element and the control contacts in series when the control contacts engage each other.

3. A plug fuse, comprising a body consisting of a head section of transparent material and a movable foot section, a threaded contact shell mounted on said body, an end contact on the foot end of said body, a fuse element within a compartment in said body and viewable through the head end of the body, a neon glow lamp in said compartment and beneath said fuse element, a resistance in said body, a control contact on the movable section and engageable with a control contact on the stationary portion of the body in a certain position of said movable section, an electric circuit from the end contact to the shell contact and including said resistant and lamp in series, and

another electric circuit from the end contact to the shell contact and including the fuse element and the control contacts in series when the control contacts engage each other, means for limiting the motion of the movable section.

4. A plug fuse, comprising a body consisting of a head section of transparent material and a movable foot section, a threaded contact shell mounted on said body, an end contact on the foot end of said body, a fuse element within a compartment in said body and viewable through the head end of the body, a neon glow lamp in said compartment and beneath said fuse element, a resistance in said body, a control contact on the movable section and engageable with a control contact on the stationary portion of the body in a certain position of said movable section, an electric circuit from the end contact to the shell contact and including said resistant and lamp in

series, and another electric circuit from the end contact to the shell contact and including the fuse element and the control contacts in series when the control contacts engage each other, and means for holding the movable section against complete displacement. 5

5. In a plug fuse, a body consisting of a transparent head section with a recess extended in from the bottom thereof and a foot section with a cylindrical portion extending into said recess 10 and having its outer face spaced from the side wall of the recess, a glow lamp supported within and on said cylindrical portion, and a fuse element having a central portion over said glow lamp and side portions continuing therefrom extending through the space between the wall of the recess of the cylindrical portion and supported on the cylindrical portion. 15
